UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROL APPARATUS.

1,261,510.

Specification of Letters Patent.

Patented Apr. 2, 1918.

Application filed August 11, 1916. Serial No. 114,375.

To all whom it may concern:

Be it known that I, ROBERT M. GILSON, a citizen of the United States, residing at Pittsburgh, in the county of Allegheny and State of Pennsylvania, have invented certain new and useful Improvements in Railway-Traffic-Control Apparatus, of which the following is a specification.

My invention relates to indication apparatus for railway traffic controlling devices.

I shall describe one form of apparatus and circuits embodying my invention and then point out the novel features thereof in claim.

The accompanying drawing is a diagrammatic view showing two railway switches and indication devices therefor, and one form of apparatus and circuits embodying my invention for the control of each of said indication devices by said switches.

Referring to the drawing, reference characters A and A' designate railway switches which are controlled by levers C and C' respectively, of an interlocking machine. The manner in which this control is accomplished is fully described in Patent No. 1,101,039 issued to G. R. Scattergood and H. A. Wallace on June 23, 1914. Briefly, switch A is operated by a motion plate F which is adapted to be reciprocated by a motor M comprising solenoids 10 and 11 operating a plunger 12 secured to the motion plate. The circuits (shown dotted) for the solenoids 10 and 11 are controlled by the lever C by means of a contact finger 18 which engages contact point 44 or 45 according as lever C is in the normal or reverse position respectively, so that movement of lever C from normal to reverse causes movement of switch A from the normal position (shown on the drawing) to the reversed position and the return movement of the lever to the normal position causes operation of the switch to the normal position. The positions of switch A' are controlled by lever C' in similar manner.

The movements of levers C and C' are controlled by indication apparatus as fully described in the aforementioned patent. For lever C this apparatus comprises segments K^R and K^N coacting as well understood in the art, with latches 29, controlled by magnets R and N in such manner that a complete reversal of lever C can be effected only if magnet R is energized when the lever ar-

rives in the middle of its stroke, and a complete movement of the lever in the opposite direction is possible only after a similar energization of magnet N. The magnets N and R are controlled as described in the said patent, by contact fingers 25 and 26 operated by lever C, and by a relay D responsive to reversals of current, this control being such that the magnet N can be energized only when the relay D is energized normally, closing contact 14, and the magnet R can be energized only when the relay D is energized reversely, closing contact 15, whereas neither magnet can be energized when relay D is deenergized. Magnets R' and N' of lever C' are controlled by a relay D' in similar manner.

Relay D as here shown comprises two windings f and a. Winding f is highly inductive and draws a lagging current from generator 19 through conductors 20 and 21. Winding a is supplied with current from a circuit comprising a transformer T energized from alternator 19 by conductors 22; a condenser K, a pole-changer P operated by motion plate F, line conductors 23 and 24, extending from pole changer P to the terminals of the relay D, an inductive impedance i connected in series with winding a preferably within the relay casing, which casing is indicated by the dotted outline r. The combined inductance of impedance i and winding a is substantially equal to the reactance of condenser K so that the circuit is substantially resonant. The current flowing in the circuit is limited only by the effective resistance thereof, which is quite small in comparison with the reactance of either the condenser K or the inductance of the impedance coil i and winding a. A comparatively large current flows therefore through winding a, which current, being displaced almost ninety degrees from the lagging current in winding f, coacts with the current in the latter winding to cause operation of the relay contacts. The direction in which these contacts are operated is governed by the direction of current in winding a relative to the direction of the current in winding f. The direction of the current in winding a is controlled by pole-changer P, this control being such that relay D closes contact 14 when the switch A is in its normal position and closes contact 15 when the

switch is in the reversed position. During the movement of the switch from one position to the other the contact fingers 16 and 17 of pole-changer P are short-circuited by a wire 51 so that no current can reach winding *a* and both contacts 14 and 15 are open. The relay D' is controlled in the same manner by switch A'.

A brief description of the operation of switch A by lever C is as follows:

When lever C is turned clockwise toward its reversed position, the lever is arrested after it has been moved through half of its stroke by a dog 28 on segment K^R engaging latch 29. In this position of the lever, finger 18 engages contact 45, thus closing the circuit for solenoid 11 of motor M, so that plunger 12 shifts motion plate F to the right causing reversal of switch A. During this movement of the switch relay D is deenergized, as hereinbefore explained, so that the circuits of both indication magnets R and N are opened and lever C is locked in its half stroke position. When, however, the switch arrives in its reversed position, relay D is energized reversely, closing at contact 15 the circuit for magnet R, thus unlocking the lever to permit its movement to the reversed position. The operation of the switch in the opposite direction is effected in a similar manner by the return movement of the lever to normal.

The apparatus for the control of switch A' is operated in similar manner by lever C'.

Signals governing traffic over the switches are controlled by levers C and C', as well understood in the art. It is therefore important that each lever always is in a position corresponding to the position of the switch which it governs, which is secured as described above, by arresting the lever in the half-stroke position until a full movement of the switch has been effected. As was pointed out hereinbefore, the locking of the levers C and C' in their center positions is secured by the deenergization of relays D and D' respectively. Ordinarily the deenergization of the relays is assured only by short-circuiting the conductors 23 and 24 at the pole-changer. But it may happen, due to a variety of circumstances, that this short circuit is rendered partially or wholly ineffective, as, for instance, in case of a break 60 in wire 23 of the circuit for winding *a* of relay D'. If now the conductors 23 and 24 of relays D and D' are crossed, as indicated by dotted connections 62, relay D' receives current from transformer T, which current would operate the relay contacts and cause release of lever C' independently of any movement of switch A' if the current had sufficient strength and the

proper phase displacement from the current in the other relay winding *f*. The last- 65 mentioned conditions are prevented by my invention, as I shall now explain.

The circuit now fed from transformer T comprises at one end condenser K and at the other end the windings *a* and impedances *i* of the two relays D and D' connected in parallel. The circuit has, in comparison with the normal resonant circuits for windings *a* of relay D and D', the same condensive reactance but only half the inductive reactance. Only an approximate half of the condensive reactance of the circuit, therefore, is counterbalanced by the inductance of the circuit, so that the circuit is no longer resonant and permits but a 80 small leading current to flow from transformer T, half of this current flowing through the windings *a* of each relay. This current would be unable to operate the relay contacts even under the best phase relation to the currents in the other winding *f*. Actually, however, the current in winding *a* of each relay has considerable lead and the current in winding *f* has considerable lag, so that the currents are displaced in 90 phase nearly 180 degrees. Thus both relays D and D' are effectively prevented from operating their contacts, making it impossible to effect an operation of either lever C or C' until the circuits are restored to their 95 normal conditions.

Although I have herein shown only one form of apparatus and circuits embodying my invention, it is understood that various changes and modifications may be made 100 within the scope of the appended claim without departing from the spirit and scope of my invention.

Having thus described my invention, what I claim is:

In combination, two railway traffic controlling devices, indication apparatus for each device including an induction motor having two windings, a source of alternating current, two circuits supplied with current from said source and controlled by said two devices respectively and including respectively one winding of each motor, each of said circuits including an inductance adjacent one end and a condenser adjacent the other and each circuit being tuned to resonance at the frequency of said source, and means for supplying the other winding of each motor with current from said source.

In testimony whereof I affix my signature 120 in presence of two witnesses.

ROBERT M. GILSON.
